CLAIM

The ornamental design for a lighting fixture as shown and described.

DESCRIPTION

This application is related to commonly assigned, co-filed U.S. design patent application Ser. No. 29/792,011, filed on Feb. 25, 2022, by Adami et al., entitled "Lighting Fixture"; commonly assigned, co-filed U.S. design patent application Ser. No. 29/792,012, filed on Feb. 25, 2022, by Adami et al., entitled "Bench"; commonly assigned, co-filed U.S. design patent application Ser. No. 29/792,013, filed on Feb. 25, 2022, by Adami et al., entitled "Path Light"; and commonly assigned, co-filed U.S. design patent application Ser. No. 29/792,014, filed on Feb. 25, 2022, by Adami et al., entitled "Bench End", which applications are incorporated herein by reference in their entireties.

FIG. 1 is a front right perspective view of a lighting fixture from below, in a first embodiment according to the new design;

FIG. 2 is an enlarged front right perspective view from below thereof;

FIG. 3 is an enlarged front left perspective view from below thereof;

FIG. 4 is an enlarged front right perspective view from above thereof;

FIG. 5 is an enlarged front left perspective view from above thereof;

FIG. 6 is an enlarged front elevational view thereof;

FIG. 7 is an enlarged right side elevational view thereof;

FIG. 8 is an enlarged left side elevational view thereof;

FIG. 9 is an enlarged rear elevational view thereof;

FIG. 10 is an enlarged top view thereof;

FIG. 11 is an enlarged bottom view thereof;

FIG. 12 is a bottom perspective view of a second embodiment;

FIG. 13 is a bottom perspective view of a third embodiment; FIGS. 14-24 show the first embodiment of the lighting fixture thereof, in an illuminated state;

FIG. 25 shows the second embodiment of the lighting fixture thereof, in an illuminated state; and,

FIG. 26 shows the third embodiment of the lighting fixture thereof, in an illuminated state.

(Continued)

The broken lines in the drawings illustrate portions of the lighting fixture which form no part of the claimed design. The long dash-short dash lines in the drawings represent a boundary of the claimed design.
